US00D936528S

(12) **United States Design Patent** (10) **Patent No.:** **US D936,528 S**
(45) **Date of Patent:** **** Nov. 23, 2021**

(54) **EXERCISING BIKE FRAME COVER**

(71) Applicant: **Shenzhen Naisi Trading Co., Ltd.**,
Shenzhen (CN)

(72) Inventor: **Shiming Xiang**, Changde (CN)

(**) Term: **15 Years**

(21) Appl. No.: **29/767,155**

(22) Filed: **Jan. 20, 2021**

(51) **LOC (13) Cl.** **21-11**

(52) **U.S. Cl.**

USPC **D12/126**

(58) **Field of Classification Search**

(57) **CLAIM**

The ornamental design for an exercising bike frame cover, as shown and described.

DESCRIPTION

FIG. 1 is a front perspective view of an exercising bike frame cover showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front elevation view thereof, illustrated in an unfolded configuration.
